Patented May 14, 1957

180,287

SOFT DRINK DISPENSER

Lynn E. Lagarde, Atlanta, and Horatio J. Forbes, Jr.,
Decatur, Ga., assignors to The Coca-Cola Company,
New York, N. Y., a corporation of Delaware

Application February 23, 1956, Serial No. 40,287

Term of patent 14 years

(Cl. D2—3)

Fig. 1 is a perspective view of a soft drink dispenser embodying our new design;

Fig. 2 is a rear or end view of said dispenser;

Fig. 3 is a side view thereof;

Fig. 4 is a front view; and

Fig. 5 is a top view of said dispenser.

Both sides of the soft drink dispenser are identical.

We claim:

The ornamental design for a soft drink dispenser, as shown and described.
